SWEN R. SWENSON, OF NEW HAVEN, CONNECTICUT, ASSIGNOR, BY MESNE ASSIGNMENTS, TO THE MOTOR RADIATOR & MANUFACTURING CORPORATION, OF NEWARK, NEW JERSEY, A CORPORATION OF DELAWARE.

RADIATOR.

Application filed July 14, 1920. Serial No. 396,254.

To all whom it may concern:

Be it known that I, SWEN R. SWENSON, a citizen of the United States, and a resident of New Haven, in the county of New Haven and State of Connecticut, have invented certain new and useful Improvements in Radiators, of which the following is a specification.

This invention relates to radiators and is more especially directed to a radiator of the type adapted for use in combination with an internal-combustion engine.

The object of the invention is the provision of a core for radiators of this character which is simple in construction, cheap to manufacture, and of high heat-radiating capacity.

To accomplish the object of this invention and to improve generally upon devices of this character, the core is composed of a plurality of parallel plates of thin sheet metal, each of which plates is stamped to provide successive series of preferably cup-like or frusto-conical projections extending in opposite directions from the plate, certain of which projections serve to space apart the adjacent plates. The side edges of successive pairs of plates are joined together to form a water passage. The projections extending from each plate of a pair toward the remaining plate to space apart said plates preferably contact with the surface of the coacting plate and are of relatively slight depth. The remaining projections of each plate are of somewhat greater depth and a portion thereof contact with and are soldered or otherwise connected to similar projections of the adjacent plate of the contiguous pair. Such of these latter projections as do not contact with similar projections extend approximately half way across the air passages. The projections extending into the air passages form pockets connecting with the water passages and are arranged in a staggered relation. By having only so many of the water pocket projections of each plate in contact with like projections of the adjacent plate of the contiguous pair as are necessary to give to the core sufficient strength to withstand the

pressure of the water, and having the remaining water pocket projections offset from each other or staggered, the air in traversing the air passages is reflected from one plate to the other and is also deflected alternately upwardly and downwardly and is therefore swirled around in such a manner that all of it comes in contact with the metal of the plates.

In the accompanying drawings is disclosed a specific embodiment of my invention wherein—

Fig. 1 is a front elevation of a radiator embodying the invention;

Fig. 2 is a side elevation of one face of a water tube;

Fig. 3 is a side elevation of the other face of a tube;

Fig. 4 is an enlarged fragmentary front elevation of a core;

Fig. 5 is a section on line 5—5 of Fig. 2.

Interposed between the upper and lower water tanks 1 and 2, respectively, of a radiator is the core or cooling unit 3. This unit is composed of a succession of parallel plates having offset side edges, the offset edges of each pair of plates being arranged to contact with each other to space apart the plates of the pair, and which offset edges are soldered or otherwise permanently joined together, whereby are formed the water passages. Vertical rows of relatively small projections 4 are stamped from one or both plates of a pair in the same direction that the edges are offset, and said projections are so arranged that they extend from one plate of the aforementioned pairs to the other and cooperate with the offset edges to space apart the plates of a pair to form water passages. These projections may extend alternately from each plate of a pair or they may all extend from a single plate. Arranged vertically of the plates and near the edges thereof are rows of relatively large stamped projections 5 which are extended from the plate in a direction opposite to that of the projections 4. Each of the projections 5 of a plate contact with a similar projection of the adjacent plate of the contiguous pair and said contacting projections are joined to

gether by means of solder or the like. By means of these contacting projections the adjacent plates of two pairs of plates are spaced from each other to form an air passage. Also there are provided on each plate the stamped projections 6 of substantially the same size as the projections 5 and which extend from their respective plates in the same direction as the projections 5 of the same plates. These projections 6 are so arranged upon their plates that when the plates are assembled to form a radiator core, each projection 6 is offset from each projection 6 of the other plate of the pair.

15 For convenience of manufacture the plates may advantageously be grouped into sections before the core is assembled, each section being composed of a pair of plates. For instance, a sheet of metal of a width 20 equal to twice the depth of the finished core may have its side edges and a narrow strip along its center line offset in the same direction and stamped to provide on either side of its central strip the proper projections, 25 after which the sheet is folded along the center line to bring into contact the side edges thereof, which are then joined together, or, two properly-stamped strips with offset edges may be positioned with the offset 30 edges in contact and the side edges joined together. Instead of proceeding in this manner, a strip a trifle longer than the height of the core properly stamped and with its edges offset may be folded about a trans- 35 verse line, the side edges joined together, and the closed end of the section opened to provide a passage through the section. The grouping of the plates according to any of these methods forms a water passage section. 40 Other methods of assembly, such as the grouping of the plates to form air passage sections, will suggest themselves to one skilled in the art of making radiators. The faces of the projections 5 are tinned after 45 the plates have been formed into sections, after which such sections are grouped together with the projections 5 of each plate in contact with the adjacent plate of the contiguous water passage section, and the tinned projections sweated together.

50 It is, of course, understood that the particular device shown and described in the present application illustrates merely a preferred form of construction and an arrangement of parts, which, it has been found, will successfully carry out the principles of my invention, and that various changes and modifications of details may easily be made without departing from the spirit of my invention as defined in the appended claims.

60 What I claim is:

65 1. A radiator core comprising a plurality of plates arranged in pairs with the side edges of each pair of plates joined together,

projections integral with and extending from the faces of each plate serving to space apart adjacent plates and other projections extending from each plate toward the adjacent plate of the contiguous pair of plates, 70 said projections on each plate being offset from any projection on the said adjacent plate of the contiguous pair.

2. A radiator core comprising a plurality of plates arranged in pairs with the side 75 edges of each pair of plates joined together, a row of projections intermediate the edges of one plate of a pair serving to space apart the plates of a pair, a row of projections adjacent each edge of a plate extended in the 80 opposite direction from said intermediate row, said projections serving to space apart the adjacent plates of contiguous pairs, and other projections on each plate extending from said plate toward the adjacent plate 85 of the contiguous pair, said last-named projections on each plate alternating with projections on the other.

3. A radiator core comprising a plurality of plates arranged in pairs with the side 90 edges of each plate offset and joined to the side edges of the other plate of the pair, rows of projections integral with and extended from said plates in opposite directions and serving to space apart adjacent plates, and additional projections extending from adjacent plates of contiguous pairs into the space 95 between said plates, each of said projections on one plate being offset from the projections on the other plate. 100

4. A radiator core comprising a plurality of plates arranged in pairs with the side edges of each pair of plates joined together, a row of projections integral with and extending from one face of each plate and contacting with the other plate to space apart the plates of each pair and other projections integral with each plate extending from said plate toward the adjacent plate of the contiguous pair, certain of said projections on each plate being offset from each projection on the other plate. 105

5. A radiator core composed of a plurality of sections, each section comprising a pair of plates with the side edges thereof joined together, a row of projections extending from one plate of the pair and contacting with the other plate to space apart said plates, projections integral with and extending from each of said plates toward the adjacent plate of a contiguous pair, certain of said last named projections being in register with projections on said adjacent plate and the remainder of said last named projections being offset from any projection of said adjacent plate. 115

6. A radiator core composed of a plurality of sections, each section comprising a pair of plates having offset edges joined together, a row of projections intermediate 130

the edges of one of said plates extending to the other to space apart said plates, a row of projections adjacent each edge of a plate extended in the opposite direction from said intermediate row and in register with the projections of a similar row on the adjacent plate of the contiguous section, and other

projections on each plate extending toward the adjacent plate of the contiguous pair, said last-named projections alternating with 10 the similar projections on said adjacent plate.

SWEN R. SWENSON.
